206,260

MACHINE FOR CLEANING BOWLING SCORE CARDS AND THE LIKE

Carl R. Yeaman, Los Angeles County, Calif., assignor to Sav-On Draperies, Inc., Los Angeles, Calif., a corporation of California

Filed Feb. 16, 1966, Ser. No. 1,067

Term of patent 14 years

(Cl. D9—2)

FIG. 1

I claim:

The ornamental design for a machine for cleaning bowling score cards and the like, substantially as shown.
